UNITED STATES PATENT OFFICE.

EDWARD PICKETT, OF INDIANAPOLIS, INDIANA.

CLAMP FOR BIAS-CUTTING MACHINES.

1,162,727.

Specification of Letters Patent. Patented Nov. 30, 1915.

Application filed July 23, 1915. Serial No. 41,459.

To all whom it may concern:

Be it known that I, EDWARD PICKETT, a citizen of the United States, residing at Indianapolis, county of Marion, and State of Indiana, have invented certain new and useful Improvements in Clamps for Bias-Cutting Machines, of which the following is a full, clear, and exact description.

This invention relates to fabric cutting machines, and has for an object to provide a clamp for a machine of this type, which operates to prevent whipping back of the fabric from the knife after each cut.

In connection with the building of tires, machines are employed for cutting bias strips from a roll of rubber treated fabric, such strips subsequently being wound on to a ring core to form the carcass of the tire.

The bias cutting machine embodies essentially a stock roll for rubber treated fabric, a vertically reciprocating knife set at an oblique angle to the path of travel of the fabric for cutting bias strips from the fabric, a horizontally reciprocating finger bar which grasps the cut edge of the fabric after each descent of the knife and measures off a suitable width of fabric to be cut upon the next descent of the knife, and an endless conveyer which carries the bias cut strips away from the knife. A disadvantage hitherto existing in a machine of this type, is that the fabric, due to its being tensioned somewhat upon being drawn forward under the knife by the finger bar, whips back toward the stock roll after the knife has descended, the result being that at times the finger bar can only grasp a portion of the cut edge instead of grasping the entire cut edge. This necessitates frequent stops and considerable waste of material. To obviate this disadvantage, the present invention provides a clamp which anchors the fabric stationary near the knife during the cutting operation and until the finger bar again grasps the fabric after each cut, as will hereinafter be more fully described.

With the above and other objects in view the invention consists in the novel details of construction and combination of parts hereinafter fully described and claimed, it being understood that various modifications may be resorted to within the scope of the appended claims without sacrificing any of the advantages or departing from the spirit of the invention.

The invention can be readily understood

from the following description taken in connection with the accompanying drawing, in which:

Figure 1 is a fragmentary plan view of a bias cutting machine equipped with my invention; Fig. 2 is a fragmentary detail plan view showing the clamp and operating mechanism; Fig. 3 is a fragmentary detail side elevation showing the clamp controlling trigger and release therefor; Fig. 4 is a fragmentary sectional view on the line 4-4, Fig. 2; Fig. 5 is a fragmentary sectional view on the line 5-5, Fig. 2; Fig. 6 is a fragmentary sectional view on the line 6-6, Fig. 3.

Referring now to the drawings, in which like characters of reference designate corresponding parts in the various views, 10 designates a vertically reciprocating knife 75 which coacts with a shear 11 in cutting bias strips from a web of rubber treated fabric, supported upon a feed table 12. A finger bar 13 is reciprocated horizontally toward and away from the delivery side of the 80 knife, by a rack and pinion device 14. The finger bar is equipped with fingers 15 which grasp the cut edge of the fabric at the inward limit of movement of the bar, the fabric edge being raised up from the shear 85 11, to permit of the fingers closing thereon. The fingers release the fabric at the outward limit of movement of the finger bar after the strip has been severed from the supply, the bias cut strip gravitating on to an endless 90 carrier 16, and being removed thereby from the knife. The whole mechanism is supported upon a frame 17.

In carrying out the invention a clamp 18 is positioned to anchor the fabric on the 95 table 12 at the feed side of the knife, the clamp being disposed parallel to the knife and being of sufficient length to engage the entire width of the web of fabric. The clamp is provided with a vertical stem 19 100 which is slidably fitted in a bearing 20 carried by the frame 17. Adjustably mounted on the stem is a stop 21, and clamped to the frame 22 of the knife is a horizontally extending finger 23 which engages the stop 21 105 during the latter portion of the upstroke of the knife, thereby raising the clamp with it. This engagement is so timed that the knife is raised out of the cut and the fingers of the finger bar have been inserted underneath the 110 knife and have taken a firm hold throughout the cut edge of the fabric before the clamp

releases the fabric and begins to raise with the knife.

The clamp is locked in raised position while the finger bar makes its outward stroke to draw a predetermined amount of the fabric underneath the knife, and to accomplish this a trigger 24 is pivoted as shown at 25 on the clamp, and is pressed by a spring 26 to seat on top of an upright stem 27, carried in a bearing 28 on the table 12, this engagement being so timed to occur at the upper limit of movement of the clamp and prevent gravitation of the clamp.

In order that the clamp may be released to gravitate and anchor the fabric upon the table, a rock lever 30 is pivoted intermediate its ends as shown at 31 on the frame and is slidably and pivotally connected at the inner end to the trigger stem 27, the outer end of the lever being slidably and pivotally connected to a cam 32 on the frame. A rod 33 is fixed to the finger bar, and moving outward with the bar, rocks the cam 32, which in turn depresses the outer end of the rock lever with a resultant raising of the inner end of the lever together with the trigger stem 27, whereby the trigger is tripped and releases the clamp to drop with the knife. The stop 21 rides on top of the finger 23 during descent of the clamp and knife.

In operation, the clamp and knife come down together, but the clamp strikes first and anchors the fabric, due to there being a greater distance between the stop 21 and clamp 18 than between the finger 23 and cutting edge of the knife, then the knife goes on and makes the cut. The finger bar then releases the severed strip and makes an inward stroke, the knife raising meanwhile sufficiently on its upstroke to let the fingers under and grasp the cut edge of the fabric supply. The knife finger 23 reaches the clamp stop 21 and raises the clamp to release the fabric just before the finger bar makes its outward stroke. The finger bar then makes its outward stroke carrying a measured width of fabric under the knife and halts to hold the fabric taut 50 for the next cut. Simultaneously with the halting, the trigger is tripped and the clamp freed to come down with the knife and again anchor the fabric on the table, as above described.

Having thus described my invention, what I claim and desire to protect by Letters Patent is:—

1. A machine for cutting strips from a web of material embodying a knife, a finger bar on the delivery side of the knife for drawing the material forward under the knife, a clamp positioned on the feed side of the knife for anchoring the material un-

til the finger bar grasps the same after each cut, and means for maintaining the clamp 65 in inoperative position while the finger bar draws the material under the knife.

2. A machine for cutting strips from a web of material embodying a knife, a finger bar for drawing the material forward under 70 the knife, a clamp for anchoring the material near the knife until the finger bar grasps the same after each cut, means operated by the knife for then raising the clamp from the material, means for holding 75 the clamp in raised position while the finger bar draws forward the material to be cut, and means operated by the finger bar for releasing said holding means.

3. A machine for cutting strips from a 80 web of material embodying a knife, a finger bar for drawing the material forward under the knife, a clamp adapted to gravitate and anchor the material near the knife, a connection between the knife and clamp where 85 by the clamp is raised by the knife after the finger bar grasps the material, means for locking the clamp in raised position while the finger bar is drawing the material under the knife, and a connection between 90 the finger bar and said means for freeing the clamp to drop with the knife to its operative position.

4. A machine for cutting strips from a 95 web of material embodying a knife, a finger bar for drawing the material forward under the knife, a clamp disposed to anchor the material near the knife, a stop carried by the clamp, a finger carried by the knife 100 timed to intercept the stop and move the clamp to inoperative position after the knife has withdrawn sufficiently to let the finger bar under and grasp the cut edge of the material, and means for maintaining the clamp in inoperative position while the finger bar draws the material under the knife. 105

5. A machine for cutting strips from a web of material embodying a knife, a finger bar for drawing the material forward under the knife, a clamp disposed to anchor the 110 material near the knife until the finger bar grasps the material after each cut, a connection between the knife and clamp adapted to then move the clamp to inoperative position, a trigger device for locking the clamp 115 in said inoperative position while the finger bar draws the material forward under the knife, and means carried by the finger bar for releasing the trigger device at the outer limit of movement of the finger bar whereby the clamp is freed to gravitate to operative position.

Signed at Indianapolis, county of Marion, and State of Indiana, this 20th day of July, 1915.

EDWARD PICKETT.
